CLAIM

The ornamental design for a holder for an electronic memory card, as shown and described.

DESCRIPTION

The patent or application file contains at least one drawing executed in color. Copies of this patent or patent application publication with color drawing(s) will be provided by the Office upon request and payment of the necessary fee.

1. Holder for an electronic memory card

Fig. 1.1 is a front view of a holder for an electronic memory card; and

Fig. 1.2 is a back view thereof.

Electronic memory card.
